UNITED STATES PATENT OFFICE.

MARTIN ELZAS, OF LOS ANGELES, CALIFORNIA.

COIN-CONTROLLED APPARATUS.

No. 888,600.

Specification of Letters Patent.

Patented May 26, 1908.

Application filed April 13, 1907. Serial No. 368,069.

To all whom it may concern:

Be it known that MARTIN ELZAS, a citizen of the United States, residing at Los Angeles, in the county of Los Angeles and State of California, have invented certain new and useful Improvements in Coin-Controlled Apparatus, of which the following is a specification.

My invention relates to a coin controlled machine, which may be used either as a game apparatus, or as a vending apparatus, being adapted to be controlled by a coin, as above stated; or a similar token.

I have shown my improved machine as a game apparatus, and my object is to provide a simple and cheap construction which shall be positive in its operation and free from tampering, and which will operate only when the proper token is used, and the push rod actuated.

My invention resides further in the construction, arrangement and operation hereinafter described with reference to the accompanying drawings, in which

25 Figure 1 is a vertical, longitudinal section through the casing of the machine, showing the mechanism in elevation, and Fig. 2 is a perspective view of the operating levers employed in said mechanism.

30 Referring to the figures, the casing 1 is provided with a cover 2 and a removable front plate 3. A dome-shaped casing 4, preferably constructed of glass, is provided with a lower circumferential flange by which the same is 35 locked in position upon the cover 2 by the clamps 5. I preferably line the interior of said casing 4 and at the base thereof with a rubber or other cushioning layer and I also arrange a ring of similar material upon the 40 upper face of the flange in order to protect the same when the clamps 5 are in position.

Mounted centrally through the cover 2 and vertically movable within the casings 1 and 4 I arrange a stem 6 having a circular 45 plate 7 fixed to the upper end thereof, and located within the glass casing 4. On the plate 7 I arrange a series of blocks closely resembling dice, which form the game portion of this machine. On one of the dice I mark a 50 series of letters A, B, etc., representing horses in a race, and on two of the other blocks I mark the odds at which the horse wins. On the remaining block I mark the word "Trade". Thus it will be seen that should a 55 person play a certain horse at the prevailing odds to finish first, second or third and the

blocks fall with the marks uppermost corresponding to his bet, the person will win, and receive a suitable reward according to my idea. On the other hand however, should the blocks not fall to enable him to win, the block marked with the word "Trade" will, of course, show, and it is my further idea to give the value of the inserted token in trade.

The mechanical means forming a part of this invention for agitating the blocks within the casing 4 will now be described.

Arranged through the cover 2 of the casing 1 and extending downwardly therein at the opposite end to the casing 4 is a coin chute 8, 70 into which the coin or similar token is adapted to be inserted. Pivotaly mounted at 9 to the casing 1 is a lever 10, having an enlarged portion 11 at one end thereof provided with a slot or opening 12 adjacent the chute 8, and into which the coin is adapted to be projected from said chute and held from displacement by means of the transverse strips 13 spacing the opening 12 and also by means of the spring 14 attached to 80 the lower portion of the chute 8 and projecting downwardly in proximity to the opening 12. A push rod 15 is vertically movably mounted through the cover 2, and is provided inside of the casing with an integral 85 plate 16 mounted in girders 17 and slideable therein, said plate and said push rod being normally held upward by a coil spring 18 attached to said plate and to the cover 2, and said plate 16 being provided with a concavely 90 cutaway lower end adapted when the plate is depressed to fit about the contour of the coin within the slot 12. The lever 10 is normally held in a horizontal position by a coil spring 19 attached thereto and to the casing 95 1 beyond the pivot 9, the downward movement of this end of the lever under pressure of spring 19 being regulated by a stop 20. Swingingly mounted in ears extending from the end of the lever 10 adjacent to spring 19 100 is a trigger block 21 having one face thereof held normally against the end of lever 10 by a leaf spring 22 mounted on said lever 10 and bearing on the upper face thereof.

On the actuation of the push rod 15 to depress the coin-holding end of lever 10, the end of said lever carrying the trigger 21 will be thrust upward, trigger 21 striking the nose 23 of a lever 24 pivotally mounted at 25 to the casing 1. The lever 24 has an elongated hammer end 26, on which the lower end of the stem 6 normally rests, and said lever is drawn

to its normal horizontal position after actuation by the trigger 21 by means of a coil spring 27 connected thereto and to the casing 1. Upon the release of the pressure on the push rod 15, after the coin within the slot 12 has been thrust therefrom into the coin receptacle 28, the trigger 21 will be returned, sliding past the nose 23 by virtue of its movable mounting, to its normal position by means of the spring 19. The spring 27 will thereupon draw the nose end 23 of the lever 24 downward, thrusting the hammer end 26 upwardly to strike the stem 6 and thereby violently agitating the marked blocks within the glass casing 4. A guide bracket 29 is fixed about the stem 6 to the casing 1 to prevent said stem wabbling when struck by the hammer 26. A suitable push button or knob 30 is also provided on the upper end of the push rod 15 for the reception of the end of the finger usually used to depress said rod.

Having fully described my invention I claim:

1. In a device of the character described, 25 the combination of a coin chute, supporting means for the marked blocks, a pivoted lever arranged beneath said supporting means, a second lever arranged to swing said first named lever away from said supporting 30 means, and having a swinging block mounted thereon to allow said levers to pass on returning to the normal position after actuation,

springs for returning said levers to actuate said supporting means, said last named lever having an opening for the reception of the 35 coin from said chute, and a vertically depressible member adapted to project within said coin opening to remove said coin and rock said lever, substantially as described.

2. In a device of the character described, 40 the combination of a coin chute, supporting means for the marked blocks, a pivoted lever arranged beneath said supporting means and provided with a rearwardly projecting nose, a second pivoted lever arranged to swing said 45 first named lever, having a swinging block pivoted upon its forward end to engage said nose upon one stroke and to pass the same on its return to the normal position, springs for returning said levers to actuate said supporting means, said second lever having an opening formed in its rear end for the reception of the coin from said chute, and a vertically depressible member adapted to be projected within said opening and to strike said coin to 50 remove the same and actuate said levers, substantially as described.

In testimony whereof I affix my signature in presence of two witnesses:

MARTIN ELZAS.
